CLAIM

The ornamental design for a handle for a pre-inked mount, as shown and described.

DESCRIPTION

FIG. 1 is a perspective view of a handle for a pre-inked mount showing our new design, illustrating the distinctively shaped handle of our invention;

FIG. 2 is a front view thereof;

FIG. 3 is a rear view thereof;

FIG. 4 is a left side view thereof (the right side view is a mirror image of the left side view); and,

FIG. 5 is a top plan view thereof.

The bottom is plain and unornamented.

FIG. 1FIG. 2*FIG. 3

FIG. 5
